Patented Dec. 22, 1914.

FIG. 1

FIG. 2

FIG. 3

FIG. 4.

UNITED STATES PATENT OFFICE.

CLARENCE H. BROWN, OF PITTSBURGH, PENNSYLVANIA, ASSIGNOR TO UNDERWOOD
TYPEWRITER COMPANY, OF NEW YORK, N. Y., A CORPORATION OF DELAWARE.

TYPE-WRITING MACHINE.

1,121,971.

Specification of Letters Patent. Patented Dec. 22, 1914.

Application filed February 20, 1911, Serial No. 609,661. Renewed March 1, 1913. Serial No. 751,614.

To all whom it may concern:

Be it known that I, CLARENCE H. BROWN, a citizen of the United States, residing at Pittsburgh, in the county of Allegheny and State of Pennsylvania, have invented certain new and useful Improvements in Type-Writing Machines, of which the following is a specification.

My invention pertains to a new and useful improvement in typewriting machines, being designed and applicable as an attachment for the line spacing mechanism of the machine.

The broad idea involved in my invention relates to the provision of means whereby the line-spacing lever or handle is prevented from turning the platen with undue speed. The quick or sharp manual movement with which the line-spacing lever is frequently thrown when the machine is used for speedy work, not only causes the line-space pawl to batter with undue force against its limit stop, but also communicates undue sharpness of movement to the platen. In converting a quick movement into a gradual movement for the performance of the desired function, I provide a connecting train including a spring between the line-space lever and the platen (preferably between the line-spacing wheel and the platen), so that the impulses received by the line-spacing lever, by which it may be thrown with great violence against its stop, do not act directly upon the platen, but upon an intermediate spring, storing therein the energy, which is more deliberately transmitted to the platen; the latter never moving faster than the spring itself can drive it, and the spring being too weak to drive the platen with undue speed.

The character of the line-space lever operation referred to is, in machines as at present manufactured, frequently productive of faulty line-spacing of the work-sheet, because the platen is turned at a speed too high to permit efficient adherence of the work-sheet to the surface of the platen; but with the spring connecting means, the platen, which is rotated by the energy stored

in the spring, initially lags behind the line-spacing lever, following it up to the set limit of the line-spacing movement with a gradual movement upon the relaxing of the spring, resulting in the maintenance of an adhering relation between the work-sheet and platen under all characters of operation of the line-spacing lever.

The different forms and means for carrying out the object of my invention here-with shown and described are simply constructive, and it is understood that certain other modifications of the basic idea may be made, which will be within the scope of the claims appended hereto.

Referring to the drawings, forming a part of this specification: Figure 1 is a horizontal view of one end of the platen roller, with my attachment in operative position thereon; Fig. 2 is an end sectional view of the ratchet mechanism for performing the line spacing movement of the platen roller, showing a face view of the preferred form of device I propose using; Fig. 3 is a longitudinal section of my preferred form in combination with a platen roller and operating knob; and Fig. 4 is a modified construction of my device.

Throughout the several views shown in the drawings numerals of reference designate like parts, in which—

1 is the platen roller commonly used on machines of this class, the same being mounted on and carried by a rod or shaft 2, on which is mounted a ratchet wheel 3. One form of mechanism for operating the ratchet, and incidentally for revolving the roll, is shown in detail Fig. 2, no claim for which is made, the same being old in the art, consisting as it does of a finger trip 4, operating bar 5, spring 6, and ratchet dog 7 carried by said bar; all of which features I disclaim as being new, the whole forming what is known as the line spacing device. The operator swings the trip or lever 4 to shift or drive back the bar or slide 5 in the usual manner, the pawl 7 usually dropping into engagement with the ratchet wheel 3 to drive the same until arrested by the usual

stop 16. During the return stroke of the parts affected by the spring 6, the ratchet wheel is usually held by detent 17.

My invention involves a suitable housing 5 or similar carrying member 8, which is rigidly secured to the ratchet 3 in any suitable manner, both of which members are loose on the shaft 2, and free to move independent of said latter member. Rigidly secured on 10 the shaft 2, adjacent to the said housing 8, is a collar 9 carrying laterally projecting integral wing members 10, which, in the preferred form, seat in the housing 8. The outer extremities of these said wings are 15 adapted to receive and retain one end of the resilient elements 11, here shown as being in the form of coil springs, the opposite ends of said springs being secured to pins or hooks 12, preferably adjustable through 20 slots 13 formed in the periphery of the housing member. If desired these pins or hooks can be made stationary instead of adjustable. The adjustable feature is of utility to vary the tension of the spring members and accommodate different grades of 25 work, or to take up the slack incidental to prolonged usage of these resilient elements.

Rigidly positioned pins or stops 14 and 15 respectively, carried by the housing 8, serve 30 to limit the rotary movement of the wings 10, and incidentally the expansion of the spring members 11. Thus a very slight, or variably increased rotary movement of the said wings, and a more or less expansive 35 movement of said springs, is possible by the position given to these stops or limiting pins.

It will thus readily be apparent, when 40 the respective parts are assembled approximately as shown, that the resilient elements will be intermediary of the respective movements of the housing and shaft, so that no matter how severe or erratic the manual line spacing action may be, the full force thereof 45 will not be communicated to the platen.

When the operator brings the line spacing mechanism into play the ratchet wheel 3 is revolved by each blow on the trip 4, but said wheel, being loosely mounted on the 50 shaft 2, does not directly effect the subsequent movement of said shaft, and of the platen roll, the effect of the blow imparted being carried to the shaft and platen through the housing 8, resilient elements 11, 55 and wing carrying collar 9; this latter member being rigidly secured to the shaft, and acting directly to rotate said shaft and roll 1.

The connection between the ratchet wheel 60 and platen shaft being of a flexible or resilient nature and capable of transmitting the movement imparted to the ratchet mechanism in modified form to the platen, the jumping or faulty line spacing which

was common is thereby reduced to a minimum and practically eliminated, so that when the platen is reversed and moved to present an already written word or line to the type for correction, there will be no variance in the line spacing, and said corrected letter or word may be inserted in the exact space occupied by the erased letter or word; as the case may be.

The only difference in the modified form shown in Fig. 4, from the preferred construction heretofore described, is that the resilient members are arranged so as to expand and shove against the wings 10, instead of being compressed, this arrangement of course necessitating changing the position of the stop and limiting pins.

What I claim as new, and desire to secure by Letters Patent, is:—

1. In a typewriting machine, the combination with a platen roller; a shaft upon 85 which said roller is mounted; a ratchet wheel loosely mounted upon said shaft; a cup-shaped housing loosely mounted on said shaft and secured to said ratchet wheel; a collar secured to said shaft and provided 90 with integral wing members and inclosed by the cup-shaped housing; spring members connecting the wing members and the housing; and adjustable means for regulating the tension of the spring members. 95

2. In a typewriting machine, the combination with a platen roller; a shaft upon 100 which said roller is mounted; a ratchet wheel loosely mounted upon said shaft; a cup-shaped housing also loosely mounted on said shaft, secured to the ratchet wheel, and adapted to turn in unison therewith; a collar secured to said shaft provided with integral wing members and inclosed by the cup-shaped housing; spring members connecting the wing members and the housing; pins carried by the housing for limiting the 105 rotary movement of said wing members; and adjustable means for regulating the tension of the spring members. 110

3. In a typewriting machine, the combination with a platen to frictionally feed a work-sheet, said platen revoluble for line-spacing, and a line-spacing lever, of a manually-operated driving train between the lever and the platen to rotate the latter on the initial stroke of said train, said train including a platen-driving spring which serves to gage or restrict the initial speed of the platen, independently of the speed of 115 manual operation, to a point where said platen will properly feed or exert traction upon said sheet. 120

4. In a typewriting machine, the combination with a platen to frictionally feed a 125 work-sheet, said platen revoluble for line-spacing, and a line-spacing lever, of a manually-operated driving train between the

lever and the platen to rotate the latter on the initial stroke of said train, said train including a platen-driving spring, which serves to restrict the initial speed of the platen, independently of the speed of manual operation, to a point where said platen will properly feed or exert traction upon said sheet, and means for limiting the extent of the step-by-step rotary movement 10 thus imparted to said platen.

5. In a typewriting machine, the combination with a platen to frictionally feed a work-sheet, a line-space wheel, and a manually-operable lever for rotating said wheel, 15 of driving means connecting said wheel and said platen for transmitting the movement of the wheel to the platen and controlling the initial speed of the platen, said driving means including a platen-driving spring between 20 said wheel and platen.

6. In a typewriting machine, the combination with a platen to frictionally feed a work-sheet, a line-space wheel, and a manually-operable device for rotating said 25 wheel, of a driving device connecting said wheel and said platen for transmitting the movement of the former to the latter, said driving device including a platen-driving spring which is connected to said wheel and 30 which serves to gage or restrict the initial speed of the platen to a point where said platen will properly feed or exert traction upon said sheet; means for limiting the extent of movement transmitted to said platen; 35 and means for limiting the relative spring tensioning movement between the line-space wheel and platen.

7. In a typewriting machine, the combination with a platen to frictionally feed a 40 work-sheet, said platen revoluble for line-spacing, and manually-operable line-spacing means for rotating said platen on the initial stroke of said means, of a driving train connecting said line-spacing means 45 and said platen for rotating the latter, said train including a platen-driving spring which serves to gage or restrict the initial speed of the platen, independently of the speed of manual operation, to a point where 50 said platen will properly feed or exert traction upon said sheet; and means for varying the tension of said spring.

8. In a typewriting machine, the combination with a platen to frictionally feed a 55 work-sheet, and a shaft on which said platen is fixed, of line-spacing mechanism including a manually-operable device, a ratchet wheel loose on said shaft and driven by said device, a member fixed to said shaft, and a 60 platen-driving spring connecting said wheel and said member together, to transmit the rotary movement of said wheel to said platen and to gage or restrict the initial speed of such movement to a point where said platen

will properly feed or exert traction upon 65 said sheet.

9. In a typewriting machine, the combination with a platen to frictionally feed a work-sheet, and a shaft on which said platen is fixed, of line-spacing mechanism including 70 a manually-operable device, a ratchet wheel loose on said shaft and driven by said device, a housing secured to said wheel, a member fixed to said shaft adjacent said housing, and a platen-driving spring within 75 said housing connected to the same and to said member, to transmit the rotary movement of said wheel to said platen and to gage or restrict the initial speed of such movement to a point where said platen will 80 properly feed or exert traction upon said sheet.

10. In a typewriting machine, the combination with a platen to frictionally feed a work-sheet, and a shaft therefor, of line-spacing mechanism including a manually-operable device, a ratchet wheel loose on said 85 shaft and driven by said device, a member fixed to said shaft adjacent said wheel and provided with a plurality of projections, 90 and platen-driving springs connecting said wheel and said projections together, to transmit the rotary movement of said wheel to said platen and to gage or restrict the initial speed of such movement to a point where 95 said platen will properly feed or exert traction upon said work-sheet.

11. In a typewriting machine, the combination with a platen to frictionally feed a work-sheet, and a shaft therefor, of line-spacing mechanism including a manually-operable device, a ratchet wheel loose on said shaft and driven by said device, a housing fixed to said wheel, a member secured to said shaft and disposed within said housing, said 100 member being provided with a plurality of projections, and platen-driving springs connecting said housing and said projections together, to transmit the rotary movement of said wheel to said platen and to gage or 105 restrict the initial speed of such movement to a point where the platen will properly feed or exert traction upon said sheet.

12. In a typewriting machine, the combination with a platen to frictionally feed a 110 work-sheet, and a shaft therefor, of line-spacing mechanism including a manually-operable device, a housing secured to said wheel, a member fixed to said shaft and disposed within said housing, said member being provided with a plurality of projections, 115 platen-driving springs connecting said housing and projections together, to transmit the rotary movement of said wheel to said platen and to restrict the initial speed of such 120 movement to a point where the platen will properly feed or exert traction upon said sheet, and means carried by said housing 125

for coaction with said projections to limit the extent of spring-tensioning movement between the platen and line-space wheel.

13. The combination of a platen to frictionally feed a work-sheet, said platen revolvable for line-spacing, and a manually-driven platen-driving train for line-spacing the same on the initial stroke of said train, and for controlling the initial speed thereof independently of the speed of manual oper-

ation, said train including a manually-operable lever or device, a pawl, a ratchet wheel, and a platen-driving spring.

In testimony whereof, I affix my signature in the presence of two witnesses.

CLARENCE H. BROWN.
